ABSTRACT OF THE DISCLOSURE

The output of a gas compressor is passed through a chamber containing a liquid level switch and then through a conduit containing a control valve and into a liquid pipeline. A differential pressure controller measures the differential pressure across the control valve and actuates a three-way valve to pass the output of the liquid level switch to the control valve when the differential pressure is below a predetermined value and actuates the three-way valve to connect an air supply to the control valve when the differential pressure exceeds the predetermined value.

This invention relates to method and apparatus for controlling a valve in the discharge line of a gas compressor to a liquid line. In past systems it has been the practice to utilize a check valve in the discharge line to prevent flow of liquid from the liquid line to the gas compressor when the gas compressor is shut down or has its outlet bypassed to its inlet to stop gas flow through the discharge line. However, it is not uncommon for check valves to have small leaks when the pressure across the valve is small. Even small leaks permit an accumulation over a period of time of enough liquid to severely damage the gas compressor.

Accordingly, it is an object of the invention to provide improved method and apparatus for preventing liquid backflow in a discharge line from a gas compressor into a liquid line. Another object of the invention is to protect a gas compressor from liquid entering the discharge conduit.

Other objects, aspects and advantages of the invention will be apparent from a study of the specification, the drawing and the appended claims to the invention.

Referring now to the drawing, which is a diagrammatic representation of one embodiment of the invention, a gas is passed through conduit 11 into the inlet of compressor 12. Bypass conduit 13, containing valve 14, communicates between the outlet of compressor 12 and the inlet of compressor 12. Valve 14 is manipulated by pressure recorder controller 15 responsive to a comparison of the desired pressure at the inlet of compressor 12 as represented by setpoint 16 with the actual pressure at the inlet of compressor 12 as indicated by pressure sensor 17. Thus, the position of valve 14 is varied to maintain the inlet pressure on compressor 12 substantially constant at the desired value. Conduit 18 communicates between the outlet of compressor 12 and an upper portion of vertically elongated tank 19. Conduit 21, containing a control valve 22, communicates between a lower portion of tank 19 and liquid transfer conduit 23, containing a pump 24. Liquid level switch 31 has a float element 32 positioned within tank 19. Conduit 33 supplies high pressure air to an inlet of liquid level switch 31. When the liquid level in tank 19 is below the switching position of float 32, liquid level switch 31 passes air from conduit 33 through line 34 to one inlet of three-way valve 35. When the liquid level in tank 19

2

rises to the switching level of float 32, switch 31 stops the flow of air through line 34 by switching line 34 from conduit 33 to a vent 37. Conduit 36 supplies high pressure air to the second inlet of three-way valve 35. When valve 35 is in a first position, line 34 is connected through output line 38 to valve 22. When valve 35 is in its second position, conduit 36 is connected through line 38 to valve 22. The presence of high pressure air in line 38 causes normally closed control valve 22 to open while the absence of high pressure air in line 38 causes valve 22 to close.

Differential gap controller 41 has first and second inlets thereof connected to conduit 21 upstream and downstream, respectively, of valve 22 to determine the differential pressure across valve 22. Controller 41 has a setpoint or threshold adjustment 42 and a gap adjustment 43. Controller 41 effectively serves as an on-off controller wherein an "on" output signal is initiated whenever the positive differential pressure across valve 22 exceeds the predetermined positive threshold value represented by setpoint 42. The term "positive" indicates that the pressure upstream (on the gas compressor side) of valve 22 is greater than the pressure on the downstream (conduit 23) side of valve 22. The "on" output signal then continues until such time as the positive differential pressure across valve 22 drops below a cut-off value represented by gap adjustment 43. The cut-off value is less than the threshold value to provide a gap or dead band. The "on" output of controller 41 actuates three-way valve 35 to its second position while the "off" output (absence of "on") of controller 41 actuates valve 35 to its first position, described hereinabove.

In the operation of the system, assume the valve 14 is open to fully recycle the output of gas compressor 12. Valve 22 will be closed and tank 19 will contain liquid up to the switching level of liquid level switch 31. The pressure on both sides of control valve 22 will be substantially equal. The differential pressure across valve 22 will be less than the threshold value of setpoint 42, controller 41 will have an "off" output, and valve 35 will be in its first position to connect line 34 to valve 22 while liquid level switch 31 connects line 34 to vent. When the fresh supply to compressor 12 becomes sufficient, valve 14 will at least partially close, causing the pressure in tank 19 and conduit 21 upstream of valve 22 to increase. When the output pressure of compressor 12 builds up enough for the differential pressure across closed control valve 22 to reach the positive threshold valve 42, controller 41 produces an "on" output signal, actuating three-way valve 35 to its second position. This results in the passage of high pressure air from conduit 36 to valve 22, causing valve 22 to open. The gas output of compressor 12 pushes the liquid out of tank 19 and conduit 21 into line 23. The drop in liquid level actuates liquid level switch 31 to connect line 34 to high pressure air supply 33. The movement of the liquid through valve 22 results in a dropping of the pressure drop across valve 22. When the differential pressure across valve 22 decreases to the cut-off value, controller 41 actuates three-way valve 35 to its first position, connecting line 34 to valve 22. The high pressure air now available in line 34 from conduit 33 maintains valve 22 in the fully open position.

At such time as the fresh gas supply to compressor 12 becomes insufficient, valve 14 is opened to recycle the output of compressor 12, dropping the pressure in tank 19. The lowered pressure permits liquid from line 23 to pass through conduit 21 into tank 19. When the level of liquid in tank 19 reaches the switching level of float 32, switch 31 transfers line 34 from air supply 33 to vent, thus venting line 38 and causing valve 22 to close. At the time the valve 22 closes, the differential pressure there-

across is less than positive threshold valve 42 and controller 41 continues its "off" output.

While valve 22 has been described as a normally closed, spring biased valve requiring positive air pressure to open, other types of valves can be utilized. If necessary, or desirable, line 38 can be connected to a pilot valve which controls the position of valve 22. While the control system has been described in terms of pneumatic components, mechanical, electrical or electro-mechanical components can be employed. Suitable pneumatic examples of switch 31 and controller 41 are the liquid level switch model 2820C-252V, manufactured by the Fisher Governor Company, and differential gap controller model X 162R, manufactured by the Taylor Instrument Company. A high gain controller having a narrow band or a biased pilot valve could be utilized instead of controller 41. While the pressure sensing lines to controller 41 are shown as connected to conduit 21 closely adjacent to valve 22, the upstream pressure sensing line can be connected to tank 19 or conduit 18, and the downstream pressure sensing line can be connected to liquid transfer line 23.

Reasonable variations and modifications are possible within the scope of the foregoing disclosure, the drawing and the appended claims to the invention.

We claim:

1. Apparatus for introducing compressed gas into a body of liquid comprising a gas compressor, means containing a body of liquid, conduit means communicating between the outlet of said compressor and the liquid containing means, a first valve means operatively connected in said conduit means, a liquid sensor switch operatively connected in said conduit means so as to be actuated by liquid passing through said conduit means from said liquid containing means before such liquid reaches said gas compressor, a power source, and control means for determining the differential pressure across said first valve means in said conduit means and for passing the output of said liquid sensor switch to said first valve means to control the position of said first valve means until said differential pressure exceeds a first predetermined value and for connecting said power source to said first valve means to open said first valve means upon said differential pressure exceeding said first predetermined value and then disconnecting said first valve means from said power source and reconnecting said first valve means to said liquid sensor switch upon said differential pressure decreasing to a second predetermined value.

2. Apparatus in accordance with claim 1 wherein said first valve means is positioned in said conduit means between said liquid sensor switch and said liquid containing means.

3. Apparatus in accordance with claim 2 wherein said liquid containing means comprises a pressurized liquid transfer conduit, and said liquid sensor switch is a liquid level switch.

4. Apparatus in accordance with claim 3 wherein said liquid level switch produces a first output signal when the level of liquid in said conduit means exceeds the switching level of said liquid level switch and a second output signal when said level of liquid is less than said switching level; and wherein said control means comprises differential pressure sensing means for determining the differential pressure across said first valve means

and producing a first output signal when the pressure upstream of said first valve means exceeds the pressure in said liquid transfer conduit by a predetermined positive value and producing a second output signal in the absence of said first output signal of said differential pressure sensing means, switching means having first and second inputs and an output, means for connecting the output of said liquid level switch to said first input of said switching means, means for connecting said power source to said second input of said switching means, means for connecting said output of said switching means to said first valve means to control the position of said first valve means, means responsive to said first output signal of said differential pressure sensing means to actuate said switching means to connect said second input of said switching means to said output of said switching means and responsive to said second output signal of said differential pressure sensing means to actuate said switching means to connect said first input of said switching means to said output of said switching means, either of the connection of said power source through said output of said switching means and the connection of said second output signal of liquid level switch through said output of said switching means causing said first valve means to be fully opened.

5. Apparatus in accordance with claim 4 wherein said switching means comprises a three-way valve, said power source is a source of fluid pressure, and wherein said liquid level switch connects said first input of said switching means to a source of fluid pressure to produce said second output signal of said liquid level switch and connects said first input of said switching means to a vent to produce said first output signal of said liquid level switch.

6. Apparatus in accordance with claim 5 wherein said first valve means comprises a spring biased, normally closed valve.

7. Apparatus in accordance with claim 5 wherein said differential pressure sensing means comprises a differential gap controller having a threshold setpoint and a cut-off setpoint.

8. Apparatus in accordance with claim 5 wherein said conduit means comprises a vertically elongated tank, said liquid level switch being connected in said tank, a first conduit connected between said outlet of said gas compressor and the upper portion of said tank above said liquid level switch, and a second conduit connected between the lower portion of said tank and said liquid transfer conduit.

9. Apparatus in accordance with claim 8 further comprising a third conduit connected between said outlet of said gas compressor and the inlet of said gas compressor, a valve positioned in said third conduit, and means for manipulating said valve in said third conduit responsive to the pressure at the inlet of said gas compressor.
